United States Patent Office.

HENRY F. MOORE AND JAMES S. BLAISDELL, OF MEDFORD, MASSACHUSETTS, ASSIGNORS TO HENRY F. MOORE, OF SAME PLACE.

Letters Patent No. 65,414, dated June 4, 1867.

IMPROVEMENT IN HANGING WAGON-SEATS.

The Schedule referred to in these Letters Patent and making part of the same.

TO ALL WHOM IT MAY CONCERN:

Be it known that we, HENRY F. MOORE and JAMES S. BLAISDELL, of Medford, in the county of Middlesex, and State of Massachusetts, have invented certain improvements in Hanging Wagon-Seats, of which the following is a full, clear, and exact description, reference being had to the accompanying drawings, making part of this specification, in which—

Figure 1 is a perspective view of a wagon-body having our improvements applied thereto.

Figure 2 is a plan of the same, the seat being turned over.

Figure 3 is a vertical section in the line xx of fig. 1.

The ordinary hinges used for hanging wagon-seats, where they are required to turn over in front, are bent or turned up at right angles at the centre in order to throw the seat off from the wagon, so that it will lie flat against the front board when turned over, which prevents it from being broken off by its own weight and the motion of the wagon. These bent portions of the hinges projecting above the upper edge of the wagon are, however, extremely liable to be injured or broken off, and present obstacles in the way of loading when the seat is turned over, while these hinges also require to be bolted to the front board of the wagon, which tends to weaken it at that point. Our invention has for its object to overcome these objections, and enable us to employ hinges not bent or turned up at the centre, and consists in so attaching the hinges to the body and seat of the wagon that the seat will be allowed to slide back and forth, so that when turned over it will lie flat against the front end of the wagon as required.

To enable others skilled in the art to understand and use our invention, we will proceed to describe the manner in which we have carried it out.

In the said drawings A is the body of the wagon, to the upper edge of which are secured strips a of sheet metal to strengthen and protect it from injury. B is the seat, which is attached to the body A by means of hinges C, so that it can be swung over in front out of the way, as is often required when loading. The portions b of these hinges are permanently secured to the seat B, while the portions c are made to slide back and forth on the upper surface of the strips a , being held in place by means of bolts or pins d , which project from their lower sides through slots e in the strips a , the bolts being provided with square heads f which slide back and forth in recesses g cut in the sides of the wagon, as seen in fig. 3, the motion of the portions c being stopped in either direction by the bolts d coming into contact with the ends of the slots e . And it will be seen that on turning over the seat B the portions c of the hinges will be drawn forward, as seen in fig. 2, to allow the seat to lie flat against the front end of the wagon without straining the hinges, and on returning the seat to its proper position the portions c of the hinges will slide back and lie compactly beneath it, as seen in figs. 1 and 3; and it will also be seen that these hinges present no obstruction in the way of loading, and are not liable to be injured or broken off, while the necessity of bolting them to the front board of the wagon, and consequently weakening it at that point, is avoided. The heads f of the bolts d fit into openings g in the portions b of the hinges, when the seat is in the position seen in figs. 1 and 3. h are pins which project from the portions b of the hinges, and when the seat is turned over into the position seen in figs. 1 and 3, pass through holes i in the portions c , and through the strips a into the body of the wagon, thus locking the seat firmly in place and preventing it from sliding forward. Any other suitable locking device may, however, be used, if preferred, or it may be dispensed with altogether, as the weight and position of the driver will tend to keep the seat in place.

We do not wish to confine ourselves to the method here shown of attaching the hinges to the wagon by means of the square-headed bolts d and slots e , as they may be attached in various other ways so as to allow the seat to slide back and forth, without departing from the spirit of our invention. Our improvements may be applied to "raved" wagons, as well as to those having plain sides, or to any other description of wagon now in use.

Claim.

What we claim as our invention, and desire to secure by Letters Patent, is—

So attaching the hinges C to the body and seat of the wagon that the seat will be allowed to slide back and forth, substantially as and for the purpose described.

We also claim, in combination with the above, the pins h , or their equivalents, for locking the seat B in place, substantially as set forth.

HENRY F. MOORE,
JAMES S. BLAISDELL.
